CLAIM

The ornamental design for a disposable speculum to cover the probe end of a tympanic thermometer, as shown.

DESCRIPTION

FIG. 1 is a perspective view of disposable speculum to cover the probe end of a tympanic thermometer taken from the side thereof showing our new design; FIG. 2 is an inverted perspective view thereof; FIG. 3 is an enlarged bottom plan view thereof; FIG. 4 is an enlarged top plan view thereof; FIG. 5 is a further enlarged side elevational thereof; and FIG. 6 is a longitudinal sectional view thereof taken along line 6—6 of FIG. 5.

FIG. 1
